(57) CLAIM

The ornamental design for a luggage, as shown and described.

DESCRIPTION

FIG. 1 is a front perspective view of an embodiment of a luggage;

FIG. 2 is a front view of the embodiment of the luggage of FIG. 1;

FIG. 3 is a rear view of the embodiment of the luggage of FIG. 1;

FIG. 4 is a right side view of the embodiment of the luggage of FIG. 1;

FIG. 5 is a left side view of the embodiment of the luggage of FIG. 1;

FIG. 6 is a top view of the embodiment of the luggage of FIG. 1; and,

FIG. 7 is a bottom view of the embodiment of the luggage of FIG. 1.

The broken lines illustrate portions of the luggage and form no part of the claimed design.

1 Claim, 7 Drawing Sheets
